UNITED STATES PATENT OFFICE.

JOHN BEAN, OF LOS GATOS, CALIFORNIA.

NOZZLE.

SPECIFICATION forming part of Letters Patent No. 700,009, dated May 13, 1902.

Application filed February 17, 1902. Serial No. 94,491. (No model.)

To all whom it may concern:

Be it known that I, JOHN BEAN, a citizen of the United States, residing at Los Gatos, in the county of Santa Clara and State of California, have invented certain new and useful Improvements in Nozzles; and I do hereby declare that the following is a full, clear, and exact description of the same, reference being had to the annexed drawings, making a part of this specification, and to the letters of reference marked thereon.

The present invention has relation to that class of nozzles adapted for connecting with a pump, reservoir, or other source of supply containing a liquid, whereby said liquid is projected in a solid or unbroken stream or jet or in a spray of the desired fineness, such nozzles being usually employed to throw insecticide or other like solution upon vegetation for the purpose of destroying the insect or fungus life thereon.

It is the purpose of the present invention to provide a nozzle that will be simple in construction, easily operated in throwing or projecting a solid stream or jet or a spray of the required fineness for the purpose intended; and it consists in a nozzle constructed substantially as shown in the drawings and hereinafter described and claimed.

Figure 1 of the drawings is a perspective view of a nozzle constructed in accordance with my invention; Fig. 2, a sectional elevation thereof; Fig. 3, a horizontal section taken on line 3 3 of Fig. 2; Fig. 4, a similar view taken on line 4 4 of Fig. 2.

In the accompanying drawings, A represents the shell or body of the nozzle, provided with a suitable coupling B, which coupling has an inlet a to communicate with the contracted outlet b in the plug-valve C when the two register with each other. This coupling B may be of any preferred construction for attachment to a tube, pipe, or hose or directly to the vessel or reservoir or other source of supply containing the liquid, although I prefer to provide said coupling with a screw-threaded socket c for connecting thereto the end of a pipe or tube.

The lower end of the plug-valve C is provided with the usual screw-threaded nipple, with which engages the screw-nut d and

washer e for tightening the plug-valve in the shell or body A, both of which valve and body are tapering, as is common in this class of nozzles.

The plug-valve C at its upper end terminates in an elliptical-formed head D, and extending from this head is the usual handle E for turning the plug-valve, said plug-valve, head, and handle being integral.

In place of having a screw F connected directly to the plug-valve C, whereby said screw would be carried by the valve when turned to act as a stop to limit the distance of rotation of the valve, I provide the shell or body A with an upwardly-extending bracket G, provided with a screw-threaded hole to receive the screw F. This screw acts as a set-screw and is entirely independent of the plug-valve C, and when brought into action the end of the screw bears with frictional contact against the elliptical-formed head D instead of using the head of the screw as a stop, thereby rendering the device much more practical and effective in limiting the rotation of the plug-valve. This set or regulating screw F acts to regulate the size of the spray by bringing the outlet b of the plug-valve C with relation to either of the side walls g h of the opening f in the shell or body A, said opening extending lengthwise of the shell or body and the side walls being parallel to each other.

It will be noticed that the side walls g h increase in width as they approach the center or on a line with the outlet b of the plug-valve C, or, in other words, the edges i are curved or segmental, bringing the greatest width of the side walls on line with the outlet in the plug-valve, so that the stream or jet from the outlet will have greater surface to impinge against, giving a much finer spray and retarding the spray at the outer edges of the side walls, and thereby rendering the operation of spraying more effective. The side walls g h, which I shall term "deflecting-walls," against which the liquid is deflected, are provided with sharp edges i, which are on a curve, and as the spray passes over these edges it attracts and carries away all scattering drops that would otherwise drip. If the edges were flat or beveled, a greater or less surface would be presented for the accumulation of the

spraying liquid, and the result would be the liability of dripping, which the sharp edges prevent.

To obtain a broad fine spray foam, the handle of the plug-valve is turned to bring the outlet of the valve at the proper angle to the spraying - wall, after which the regulating-screw is turned against the elliptical-formed head to hold the valve in position. As the nozzle becomes clogged the handle is turned in the opposite direction, which action of the valve-plug will throw out the obstruction.

The plug-valve may be locked closed or the same may be brought into position to throw a solid stream by regulating the set-screw with relation to the elliptical-formed head.

Having now fully described my invention, what I claim as new, and desire to secure by Letters Patent, is—

1. In a nozzle, a suitable shell or body having an upwardly - extending bracket and a regulating-screw engaging therewith and supported thereby, and a rotatable valve having

at its upper extremity and above the upper end of the shell or body an elliptically-formed head against which the end of the screw is adapted to impinge, substantially as and for the purpose set forth.

2. In a nozzle, a suitable shell or body having an outlet with side walls increasing in width in a direction near their center, said shell or body having a bracket extending out from the same, and a rotatable valve having an elliptically-formed head at its upper end and above the shell or body, and a regulating-screw supported by the bracket and adapted to impinge against the elliptically-formed head, substantially as and for the purpose specified.

In testimony that I claim the above I have hereunto subscribed my name in the presence of two witnesses.

JOHN BEAN.
